TELLER TRAY

John Hester Davis, Garland, Tex.

Application April 13, 1956, Serial No. 41,069

Term of patent 14 years

(Cl. D52—4)

FIG. 1

Fig. 1 is a perspective top view of a teller tray, showing my new design.

Fig. 2 is a side elevational view of the teller tray in Fig. 1.

The opposite side of the teller tray is substantially the same in appearance as the side disclosed in the drawing, except for the omission of the small auxiliary tray on the side of the bottom tray.

I claim:

The ornamental design for a teller tray, as shown and described.
